UNITED STATES PATENT OFFICE.

THOMAS HAYTON, OF TURTLE CREEK, PENNSYLVANIA.

SWITCH FOR INDUSTRIAL TRACKS.

1,130,165.

Specification of Letters Patent.

Patented Mar. 2, 1915.

Application filed October 22, 1914. Serial No. 868,020.

To all whom it may concern:

Be it known that I, THOMAS HAYTON, a citizen of the United States, residing at Turtle Creek, in the county of Allegheny and State of Pennsylvania, have invented 5 certain new and useful Improvements in Switches for Industrial Tracks, of which the following is a specification.

This invention relates to certain new and 10 useful improvements in switches for industrial tracks.

The primary object of the invention is to provide both a two and three way switch especially adapted for narrow gage industrial 15 tracks and so arranged as to automatically allow a car to pass therethrough upon the main track whether the same is approaching the switch from the main or a side switch track.

20 A further object is to provide a shiftable switch arm automatically operated by the movement of cars in one direction and mechanically shiftable for allowing the cars to pass in opposite directions and being primarily designed for cars having outwardly 25 flanged wheels.

A still further object is to provide a shiftable three-way switch arm adapted for automatic actuation by a moving car and having a steady means for each adjusted 30 position.

With these general objects in view and others that will appear as the nature of the invention is better understood, the same consists in the novel combination and arrangement of parts to be hereinafter more fully described, illustrated in the accompanying drawings and set forth in the appended claims.

40 In the drawings forming a part of this application and in which like-designating characters refer to corresponding parts throughout the several views, Figure 1 is a top plan view of a three-way switch provided with my improved shiftable switch arm. Fig. 2 is a vertical sectional transverse view taken upon line II—II of Fig. 1. Fig. 3 is a vertical longitudinal sectional view taken through the switch arm when 45 operatively positioned. Fig. 4 is a perspective view of the switch arm and its lever detached, and Fig. 5 is a top plan view of a two-way switch provided with a similar switch arm.

50 Referring more in detail to the drawings the main track 10 is illustrated extending

in a substantially straight direction and having siding or switch tracks 11 and 12 communicating therewith and entering the said main track from opposite directions 60 and at the same point whereby the employment of a three-way switch is rendered essential.

The device is herein illustrated in connection with a narrow-gage track and is especially designed for industrial roads, in which the flanges of the wheels are arranged for engagement with the outer sides of the rails. The wheels of the cars are adapted to travel upon the rails 13 of each of the 70 tracks herein illustrated, a pair of such wheels being indicated at 14 in Fig. 2 and when positioned thereon the flanges 15 of the wheels enter the longitudinal grooves 16 upon the outer sides of said tracks, the intervening surface 17 of the road-bed being usually of the uniform height of the rails.

A four-sided pit 18 is arranged at one side of the main track 10 forming an interruption in one side rail thereof, the said pit being adapted for positioning a shiftable switch arm or block 19 therein and having a base plate 20 at the bottom of the pit for mounting the block thereon. The said block 19 is formed as illustrated in Fig. 4 having 85 flared opposite ends one of which designated 21 a greater arcuate length than the opposite end 22 thereof and both of said ends being arcuate in form and conforming to the curvature of the opposite shorter and 90 longer ends 23 and 24 respectively of the said pit 18.

The block 19 is provided on its under face and adjacent the end 22 thereof with a depending pivot post 25 adapted to be normally positioned within a socket 26 of the plate 20 whereby the block is swingingly mounted upon the plate and providing for the shifting movement of the block end 21 within the pit. The block is provided with 95 a relatively short rounded depending pin 27 adjacent its end 21 and the said pin is adapted to enter any desired one of the three shallow sockets 28 arranged in the plate 20 adjacent the end 24 thereof.

A hand lever 29 pivotally mounted as at 30' is pivotally connected to the under face of the block 19 by means of the link 31' and as will be apparent from Fig. 1 of the drawing, a shifting of the lever 29 may be employed for manually moving the block 19 110 so as to position the block pin 27 in any

desired one of the sockets 28, the said pin readily riding over the adjacent face of the plate 20 during such movement of the block. The movement of a car toward the switch 5 upon either of the three tracks and in a direction indicated by the respective arrows will be unimpeded by the switch block which block will allow the car to freely pass to the succeeding length of the main track. 10 With the switch block as illustrated in Fig. 1 the car approaching the same upon the track 12 will freely pass to the main track by a movement of the left-hand wheels of the car upon the side rail 30 of the block 15 and with the flanges of such wheels within the adjacent longitudinal grooves 31 thereof. When a car approaches the switch upon the track 10 the left-hand wheels will ride upon the intermediate rail 32 of the blocks 20 and with the wheel flanges in the longitudinal groove 33 thereof and by reason of the engagement of the right-hand flanged wheels of the car with the right-hand rail 13 of the main track, the switch block will 25 be automatically shifted to position the pin 27 within the central one of the sockets 28 at which time the block rail 32 will be in alinement with the advance portion of the main track left-hand rail so that the car will 30 freely pass upon the main track. Similarly, a car approaching the switch from the left hand switch track 11 will have its left hand wheel flanges engage the outer face of the left hand rail 34 of the switch block and 35 shift the block to position the pin 27 into the right-hand socket 28 to allow the passing of the car to the main track by reason of the alinement of the block rail 34 with the left-hand rail 13 of said main track. 40 It will be seen from this description of the automatic operation of the switch block from its position as illustrated in Fig. 1 that in a similar manner the block will be automatically shifted by the car entering 45 the switch so as to provide a continuous connection between the forwardly positioned portion of the main track and regardless of whichever one of the three-track portions the car is traveling over. In other words, 50 with the block positioned as illustrated in Fig. 1, a car may freely pass from the side track 12 to the main track without shifting the block, but any car approaching the switch upon either the track 10 or 11 will 55 automatically shift the block and freely pass to the forward portion of the main track. If the block is shifted for the free passage of a car therethrough from the track 11, a passing of the car from the track 12 will 60 automatically shift the block for allowing such car to freely pass to the main track.

When a car is approaching the switch from a direction opposite to that indicated

by the arrows in Fig. 1 it then becomes necessary to manually shift the block by means 65 of the lever 29 to the requisite position for allowing the car to pass to the desired track portion.

It will thus be seen that an automatically shiftable switchblock is provided which is 70 retained against accidental displacement and which affords a switch structure that is cheap and easy to construct and employs less than the usual number of separate parts.

While the forms of the invention herein 75 shown and described are believed to be the preferable embodiments thereof, it is nevertheless to be understood that minor changes may be made therein without departing from the spirit and scope of the invention 80 as claimed.

What I claim as new is:—

1. A device of the class described comprising in connection with a main track and switch tracks entering the said main track 85 and the road bed of the main track being provided with a pit, of a flaring-ended shiftable block positioned within said pit and pivoted at one end, three rail portions longitudinally positioned upon the upper side of 90 said block and adapted for engagement by the wheels of cars approaching the same upon any of the said tracks during the movement of said cars to the forwardly positioned portion of the main track. 95

2. A device of the class described comprising a main track and side tracks entering the same, the road bed of said main track being provided with a pit having curved ends at an interruption in all of the 100 said tracks, a base plate positioned in the bottom of said pit and conforming to the shape thereof and having opposite curved ends of different lengths, and provided with three sockets in its upper face adjacent its 105 longer end and a single socket adjacent the shorter end thereof, a switch block, having relatively long and short curved ends and positioned within said pit shiftably upon the said plate, a depending post carried at 110 said block in pivotal engagement with the socket at the shorter end of said plate, a pin at the longer end of said block and adapted for seating engagement in the desired one of said sockets at the longer end 115 of said plate, three rail sections longitudinally positioned upon the upper face of said block and adapted for automatic alinement with either of said tracks during the travel of a car to said switch block therefrom. 120

In testimony whereof I affix my signature in presence of two witnesses.

THOMAS HAYTON.
